UNITED STATES PATENT OFFICE

160,259

TUMBLER OR SIMILAR ARTICLE

Carl W. Gustkey, Wheeling, W. Va.

Application January 10, 1950, Serial No. 7,137

Term of patent 14 years

(Cl. D36—8)

To all whom it may concern:

Be it known that I, Carl W. Gustkey, a citizen of the United States, residing at Wheeling, county of Ohio, and State of West Virginia, have invented a new, original, and ornamental Design for a Tumbler or Similar Article, of which the following is a specification, reference being had to the accompanying drawing, forming a part hereof.

Figure 1 is a side elevational view of a tumbler or similar article showing my new design; and

I claim:

The ornamental design for a tumbler or similar article, substantially as shown.

CARL W. GUSTKEY.
